UNITED STATES PATENT OFFICE.

PAUL P. LINDEN, OF YONKERS, NEW YORK.

MACHINE FOR ATTACHING IDENTIFICATION SEALS ON SKINS.

Application filed December 27, 1927. Serial No. 242,700.

This invention relates to a new and useful machine for securing identification seals to furs, skins, silks, or the like in bolts, which are sent out to be treated, cured or dyed. In an 5 application Serial No. 242,699, filed simultaneously with this application, the identification seal disclosed herein has been claimed.

The object of the invention is to provide a machine of the class described embodying a 10 means of punching holes in the articles to which the identification seal is to be secured to, in combination with a means of placing the seal in place and crimping the seal so as to securely attach the same to the article.

15 A further object of the invention is to provide a machine of the class described of novel construction and arrangements of parts hereinafter more fully described, claimed and illustrated in the accompanying drawings.

20 Fig. 1 is a front elevational view of my improved machine.

Fig. 2 is a top plan view thereof.

Fig. 3 is a side elevational view.

25 Fig. 4 is an enlarged fragmentary front elevational view of the movable head as embodied in my improved machine, showing same in a semi extended position.

30 Fig. 5 is a similar view to that illustrated in Fig. 4, showing the movable head fully extended.

Fig. 6 is a vertical central sectional view taken on the line 6—6 of Fig. 4.

35 Fig. 7 is a transverse sectional view taken on the line 7—7 of Fig. 3.

Fig. 8 is a transverse sectional view taken on the line 8—8 of Fig. 3.

40 Fig. 9 is a fragmentary side elevational view of the identification seal plate magazine seal partly in section.

Fig. 10 is a transverse sectional view taken on the line 10—10 of Fig. 3.

Fig. 11 is a side elevational view thereof.

Fig. 12 is a transverse sectional view taken on the line 12—12 of Fig. 10.

45 Fig. 13 is a side elevational view of the identification seal magazine.

Fig. 14 is a side elevational view of the movable head operating linkage.

Fig. 15 is a rear elevational view thereof.

50 As here embodied my improved device comprises a platform 10, or base element, horizontally disposed and supported by the downwardly extended elements 11, or legs. The lever 12, provided with a handle element 13, is pivotally attached as at 14, to the arm 15, secured to and extended from the guide 16.

The slide 17 is slidably mounted in the guide 16 and has secured thereto, and extended therefrom pins 18 and 19, adapted to engage in elongated openings 20 and 21, respectively formed intermediate the lever 12. The magazine 22, or hopper is of tubular, rectangular transverse cross-section, and is secured to and extended vertically from the bracket 22', and is adapted to hold the engaging members 23, and has formed therein an opening 24, at one side thereof, for the purpose of permitting the said engaging members to be positioned or placed in the said magazine. The said engaging members are positioned or placed in a vertical column, or pile therein. The slide 17 has secured thereto, a finger member 25 adapted to engage or strike the engaging member 26, positioned at the bottom of the above mentioned vertical column. The above described construction is such that the lever 12, when manually pulled or forced outwardly, will cause the finger member 25, to engage or strike the engaging member 26, as a means of sliding the said engaging member, from the vertical column, inwardly into the elongated opening 27, or slot formed in the table 29. The lever 12 is normally held in an inward position by means of the tension spring 30, attached to the above mentioned pin 18, and to the pin 31 secured to the guide 16. The table 29 is mounted on and extended from the platform 10.

The lever 33, provided with a handle element 34, is pivotally attached as at 35, to the arm 36, secured to and extended from the guide 37. The slide 38 is slidably mounted in the guide 37 and has secured thereto and extended downwardly therefrom a pin 39, held in engagement with or in contact intermediate with the lever 33 by means of the tension spring 40, secured to the pin 39, and to the guide 37. The guide 37 is secured as at 37' by bolts, screws or the like to the extended portion 67' of the support 67. The stop 36' is mounted in and extended from the guide 37, as a means of limiting the movement of the slide 38. The cover 48' is secured as at 49' to the guide 37. The guide 37 is adapted to guide the slide 38. The magazine 41, or hopper is of tubular, rectangular cross section, and is secured to and extended vertically from the guide 37, and is adapted to hold the identification seals 42. The said identification seals 42 are positioned or placed in a vertical column, or pile in the said hopper, having their extended elements 43 and 44, extended downwardly, slidably en-

gaging the rods 45 and 46, respectively, vertically disposed in the said hopper, which is provided with an upper open end 47, as a means of permitting the said identification seals to be positioned on the rods 45 and 46, in the said hopper, as above set forth. The slide 38 is provided with upwardly side extended elements, having their extremities formed or bent inwardly as at 48, as a means of engaging or striking the identification seal, designated by the reference numeral 49, positioned in the hopper 41, at the bottom of the said pile, as a means of sliding the identification seal 49 inwardly therefrom, when the lever 33 is forced or pressed inwardly.

The said identification seal is slidably positioned as designated by the reference numeral 78, resting on the levers 79 and 80, hinged as at 81 and 82, respectively to the guide 37, the extended elements of the said identification seal, extended downwardly intermediate the levers 79 and 80. Coil springs 83 and 84 are wound co-axial on the hinge pins 81 and 82, respectively, as a means of normally holding the levers 79 and 80 in a horizontally extended position.

The pedal 50, or treadle, is pivotally secured at one extremity as at 51, to a rod 30 horizontally disposed and secured to two of the adjacent legs 11. The pedal 50 is provided with an enlarged free extremity 52, adapted to receive or support the foot of the operator of my improved device, for the purpose as hereinafter set forth. The rod 53 is secured as at 54, intermediately to the pedal 50 and is secured at its upper extremity, as at 55, in proximity to the extremity of the lever 56, pivotally mounted, intermediately as at 57, to the bracket 58, secured to and extended downwardly from the platform 10. The rod 59 is secured to the extremity of the lever 56 and is secured as at 61, to the extremity of the bellcrank 62, pivotally secured as at 63, intermediate the brackets 64 and 65, secured as at 66', by a bolt, screw, or the like and extended upwardly from the horizontally extended portion 66, of the support 67, secured to the platform 10 and extended upwardly therefrom.

A pair of links 68 and 69, are pivotally secured as at 70, to the extremity of the bellcrank 62 and are similarly secured as at 71, to the H shaped link 72, which is provided with an extended element 73, pivotally secured, at its extremity, as at 74, to the brackets 64 and 65. The link 72 is pivotally attached, as at 75 to the extended portion 76 of the movable head 77 slidably mounted vertically in an aperture formed in the above mentioned element 66, of the support 67. The above described construction is such as will permit the movable head 77 to be slid downwardly when the pedal 50 is depressed, the bellcrank 62, the links 68 and 69 and

the link 72, assuming a somewhat downward position, as designated by the reference numerals 62', 69' and 72' respectively. The movable head 77 is provided with a downwardly extended portion 85, of hollow cylindrical construction, having mounted therein a rod 86, which is provided with an enlarged lower portion 87, adapted to slidably engage in the extended portion 85 of the movable head 77. The expansion spring 88 is wound 75 or positioned on the rod 86, as a means of normally holding the rod in a downward position. The upper end of the rod 86 is normally engaged by the inwardly extended extremities 89 and 90, respectively of the levers 91 and 92, mounted as at 93 and 94, respectively, to the movable head 77 and oppositely extended horizontally therefrom through apertures formed in the said movable head. Tension springs 91' and 92' are 85 secured respectively intermediate to the levers 91 and 92 and to the movable head 77, as a means of normally holding the said levers in a horizontally extended position. The cap 95 is secured as at 96 and 97, by screws, 90 bolts, or the like to the lower extremity of the extended portion 85 of the movable head 77 and is provided with a downwardly extended element 98. The pins 99 and 100 are 95 slidably mounted in the cap 96 and are secured to and extended downwardly from the enlarged portion 87 of the rod 86.

The rod 102, or plunger is slidably mounted in the plate member 103, which is provided with a downwardly extended portion 104, having a flanged extremity 105 secured to the above mentioned platform 10. The rod 102 is extended downwardly through an aperture formed in the extended portion 104 of the plate member 103, somewhat below 105 the platform 10 and is provided with an enlarged extremity 106, having secured thereto and extended therefrom a pin 107. The tension spring 108 is secured to the pin 107 and to the above mentioned pedal 50, as a means 110 of normally holding the upper extremity of the rod 102, somewhat below the plate member 103. The links 110 and 111 are pivotally secured as at 112 and 113, respectively, to the collar 114 secured intermediately to the 115 rod 102. The links 110 and 111 are pivotally secured as at 115 and 116, respectively, to the pins 117 and 118, respectively, secured to the slides 119 and 120. The slides 119 and 120 have formed therein depressions 119' 120 and 120', and apertures 121' and 122', equally in the adjacent extremities of the said slides. The pins 117 and 118 extending through elongated openings formed in the said plate member 103. The slides 119 and 120 are slidably mounted in the plate member 103.

The above described construction is such as will permit my improved device to function as follows. The article to which my 130

identification seal is to be secured, designated by the reference numeral 121 is positioned or placed on the slides 119 and 120. By depressing the pedal 50, the movable head 77 is forced downwardly, as above set forth, causing the pins 99 and 110 to engage in the apertures formed in the extended elements of the identification seal, and forcing the said seal downwardly, the levers 79 and 80, hinging downwardly as designated by the reference numerals 122 and 123, respectively, as a means of permitting the said seal to be forced downwardly as designated by the reference numeral 124. It is understood that the pins 99 and 100 are of suitable length to extend somewhat beyond the lower extremities of the extended portions of the said seal, as clearly shown in Fig. 4, as a means of permitting the said pins 99 and 100 to perforate the said article 121. A further, or additional depression of the pedal 50, causes the free extremity 101 of the lever 56, to engage the extended portion 125, of the lever 125', and this lever engages the enlarged extremity 106 of the rod 102, and raises the rod 102, which causes the slides 119 and 120 to be forced outwardly by means of the links 110 and 111, and permits the engaging member to drop on the upper extremity of the rod 102 and be supported thereby. Upon further depression of the pedal 50, the levers 91 and 92, engage or strike the adjustable stops 126 and 127, respectively, threadedly mounted in the bracket 126', secured as at 127', to the extended portion 67' of the above mentioned support 67, causing the said levers to disengage the rod 86, permitting the rod 86 to move relatively upwards with relation to the head 77 and against the action of spring 88, which will permit the lower extremity of the cap 95, to engage the seal, as clearly shown in Fig. 5, as a means of crimping the extended portions of the said seal into the apertures formed in the said engaging members, as clearly shown in Fig. 5 which will securely attach the said seal to the said article 121.

Having thus described my invention, what I claim as new and desire to protect by Letters Patent of the United States is as follows:

1. In a machine of the class described, a movable head having a cap with a downwardly extended element attached on its bottom, a rod slidably mounted in the said head and having projecting pins at its bottom extending thru the said downwardly extended element and adapted for passing thru the openings of an identification seal, a spring normally urging the rod downwards, levers pivotally mounted on the said head and having their inner ends resting on the top of the rod for restraining possible upward motion of the rod relative to the head while the head moves downwards, stops for abutting the outer ends of the levers during downward motion of the head for freeing the rod so as to permit the same to move upwards relative to the head during the final stages of downward motion of the head for permitting the said pins to be moved from the openings in the seal, and springs for moving the said levers back to operative positions upon a raising of the head.
2. In a machine of the class described, a movable head having a cap with a downwardly extended element attached on its bottom, a rod slidably mounted in the said head and having projecting pins at its bottom extending thru the said downwardly extended element and adapted for passing thru the openings of an identification seal, a spring normally urging the rod downwards, levers pivotally mounted on the said head and having their inner ends resting on the top of the rod for restraining possible upward motion of the rod relative to the head while the head moves downwards, stops for abutting the outer ends of the levers during downward motion of the head for freeing the rod so as to permit the same to move upwards relative to the head during the final stages of downward motion of the head for permitting the said pins to be moved from the openings in the seal, and means for moving the said levers back to operative positions upon a raising of the head.
3. In a machine of the class described, a movable head having a cap with a downwardly extended element attached on its bottom, a rod slidably mounted in the said head and having projecting pins at its bottom extending thru the said downwardly extended element and adapted for passing thru the openings of an identification seal, a means for normally urging the rod downwards, levers pivotally mounted on the said head and having their inner ends resting on the top of the rod for restraining possible upward motion of the rod relative to the head while the head moves downwards, stops for abutting the outer ends of the levers during downward motion of the head for freeing the rod so as to permit the same to move upwards relative to the head during the final stages of downward motion of the head for permitting the said pins to be moved from the openings in the seal, and springs for moving the said levers back to operative positions upon a raising of the head.
4. In a machine of the class described, a movable head having a cap attached on its bottom, a rod slidably mounted in the said head, and having projecting pins at its bottom extending thru the cap and adapted for passing thru the openings of an identification seal, a spring normally urging the rod downwards, levers pivotally mounted on the said head and having their inner ends resting on the top of the rod for restraining pos-

sible upward motion of the rod relative to the head while the head moves downwards, stops for abutting the outer ends of the levers during downward motion of the head for freeing the rod so as to permit the same to move upwards relative to the head during the final stages of downward motion of the

head for permitting the said pins to be moved from the openings in the seal, and springs for moving the said levers back to ¹⁰ operative positions upon a raising of the head

In testimony whereof I have affixed my signature.

PAUL P. LINDEN.
